UNITED STATES PATENT OFFICE

LEE P. HYNES, OF ALBANY, NEW YORK, ASSIGNOR, BY MESNE ASSIGNMENTS, TO CONSOLIDATED CAR-HEATING COMPANY, INC., OF ALBANY, NEW YORK, A CORPORATION OF NEW YORK

DOOR ENGINE

Application filed August 19, 1922. Serial No. 583,041.

For a detailed description of the present form of my invention, reference may be had to the following specification and to the accompanying drawings forming a part there-
5 of, wherein

Fig. 1 is a plan and

Fig. 2 is a side view of my engine;

Fig. 3 is a horizontal section, and

Fig. 4 a partial section through the valve
10 chests;

Fig. 5 is a detail of the oscillating shaft
which the engine operates.

Figs. 6 and 7 show a modification.

My engine contains two opposed cylinders
15 of different diameters with their piston directly connected, the larger cylinder being offset or eccentric with respect to a door actuating rod which is brought out from the larger piston through the offset wall or partition between the two. The smaller cylinder acts to close the door and is adapted to have air pressure constantly maintained therein, while the larger one acts to open the door and only receives pressure when and so long as the
20 door is opened, its greater area enabling it to overcome the pressure on the smaller one with sufficient excess power to also open the door. Since the smaller cylinder is under constant pressure, I provide its piston with a
25 back seal between it and the aforesaid partition wall to prevent leakage, while it is in its static condition. I also provide an improved arrangement of check-valves which puts the admission and check ducts connected with the
30 end of each cylinder in separate branches instead of in series, and removes the speed control from the inlet side to the check side of the piston. This gives a material improvement in operation.

Referring to the drawings, 20 is the smaller cylinder, 40 the larger one. In the former is a piston 21 with the usual leather packing 22. In addition I provide a back seal in the form of a packing washer 23 which abuts against
35 the partition wall whenever the piston is in its normal door-closing position as shown in Fig. 3. The said partition is perforated for the passage of a rod 50 which rigidly connects the two pistons so that they move together. The
40 two cylinders are not concentric, but, as

shown in Fig. 4, the larger one stands out above the smaller one, so that the said rod 50 extends from the center of piston 21 to a point near the lower edge of piston 41. An actuating rod 51, overlapping cylinder 20, extends backward from a point near the upper edge of piston 41 and passes out of the casing through a grease-retaining stuffing-box 60. A connecting rod 52 is jointed to the outer end of actuating rod 51 and connects, 55 through the adjustment link 57, with a lever arm 53 which is screwed into a split clamp 56 on the oscillating door-shaft 54. As appears in Fig. 5, the shaft 54 is journalled in a triangular plate 55 seated on a suitable base-plank 58. The cylinder 20 is supplied by an air pipe 2 and cylinder 40 by an air pipe 4.

The rod 51 is guided by a suitable bore 51a formed in the wall of the smaller cylinder. Pipe 2 is connected with a source of pressure 70 supply (not shown), but no means is provided for exhausting the cylinder 20 to the atmosphere. Pipe 4 is also connected to the source of pressure supply, means being provided to connect cylinder 40 alternately to supply and 75 to exhaust by any well known type of valve which is conventionally shown at V.

Each cylinder is provided with a valve chest 70, and inasmuch as the two valve chests are duplicates, but one will be described in 80 detail. Each chest communicates with its cylinder through a main duct A spaced from the ends of the cylinder and a second duct F at the end of the cylinder, and each chest also communicates with its pressure supply pipe 2 or 4, as the case may be by means of a duct E. It is to be understood that the cylinder 20 is permanently connected to the pressure supply, and that when pressure is applied back of the larger piston 41, such pressure is acting upon the greater area of said piston 41 and therefore will overpower piston 21 and move it in a direction to force the air contained in the cylinder 20, back through the ducts A and E into the pressure supply. Thus, the air forced out of cylinder 20 will be subjected to the same cushioning restrictions that would be present if the cylinder were connected to an exhaust in the same manner as cylinder 40. On the front 100

side of piston 41 the space is normally partly closed by a plug 37 which serves as a vent to prevent accumulation of pressure on that side of the piston.

- 5 In both valve chests the inflow is freely from the duct E through a branch which includes a passage controlled by a ball check valve H to the cylinder through the duct F. A second branch leads from the duct E to the 10 duct A and includes passages controlled by valve D and ball check valve B, flow through this branch to the cylinder being normally prevented by the said check valve. The branch leading from the duct E to the 15 duct F also includes an outlet passage controlled by the valve G, the ball check valve H being so arranged as to be seated by back pressure flowing outwardly through the duct F. In practice, the outflow through duct F seats the 20 ball check valve H, so that the only outlet from F to E is through the passage controlled by the valve G. The outflow through the duct A unseats the check valve B so that there is free passage to the duct E except as the passage 25 may be restricted by the valve D.

It will now be assumed that pressure is being admitted to the cylinder 40 through the duct E. Under these conditions the pressure passes directly from the duct E into the 30 cylinder back of the piston 41, by way of the duct F forcing the two pistons to the left, as viewed in Figure 3. In this connection, it must be borne in mind that while the large piston 41 is being pressed from behind, it is 35 being checked by the small piston 21 which expels the air back into the air supply, as well as by the air expelled from its front side through the plug 37 and through the port A via the needle valve D and port E.

40 The smaller piston 21, on its out-stroke first expels the air freely through the duct A, open check valve B, needle valve D to duct E. At the same time air is being expelled outwardly through the port F to the duct E 45 via the needle valve G. But the valve G will not add any substantial restriction to the speed of the cylinder due to the fact that the air more freely passes out through the port A. Later, however, after the piston has 50 moved to a position to cover the port A the remaining air is expelled less freely through the port F, needle valve G and duct E.

On its in-stroke the smaller piston 21 sucks back (under reservoir pressure) freely from 55 the duct E through the open check valve H to the duct F. This free inflow remains the same after the piston uncovers the port A, because of the check valve B which is closed to flow from E to A. While the air is flowing out ahead of the piston 21, that air goes from the duct A to the duct E through the valves B and D in series. Therefore, the valve D may be readily used to control the engine speed.

60 Heretofore, it has been customary to place

the cushioning valve between the check valve and the entrance to the end of the cylinder and thereby to control the speed of the engine by throttling the incoming air so that the maximum power of the pressure could not be applied. By placing the valve G between the duct E and the valve H, there is no restriction whatever to the free inflow of the pressure fluid so that its maximum power is quickly applied to the piston, the speed of the engine being controlled by the throttling of the outgoing air, two checks being obtained. The first check on the small piston is by way of the port A, ball valve B and adjustable needle valve D. The second check, after port A is covered by the piston 21, is through the port F, adjustable needle valve G and the duct E. In practice, the opening through the needle valve D is larger than that through the needle valve G so that the last mentioned valve stops the door by a cushioning action. An important advantage also is obtained by placing the valves G and H in two parallel branches, the check valve being in the inlet branch and the needle valve in the outlet branch, the parts being so disposed that the outward pressure immediately seats the check valve and makes it imperative for the pressure to pass out through the valve G.

65 The valve arrangements are duplicated for the larger cylinder 40. Communication between the outside atmosphere and the space 80 within the casing is effected through an opening which is normally partially closed by a plug 37 and the opening in the wall or partition at the left of space 80 is larger than the rod 50 which passes therethrough so that the lubricant which partially fills the inter-piston chamber can flow freely through it. It is, however, desirable at times to support the rod 50 where it passes through the partition, and for that purpose, I provide at that point a bearing bushing 25 (see Figs. 6 and 7) for the said rod. This bushing has notches around its periphery to permit flow of lubricant due to the unequal size of the cylinders. This bushing 25 is screwed into the partition to give a support for the rod without obstructing the lubricant.

70 What I claim as new and desire to secure by Letters Patent is:

- 75 A door engine of the character described comprising a single acting door opening cylinder opposed by a single acting door closing cylinder of smaller diameter with an intermediate lubricating chamber, said cylinders being relatively offset, pistons in the respective cylinders, a piston rod directly connecting the pistons through said intermediate lubricating chamber, said rod being concentric with respect to one piston and eccentric with respect to the other piston, and door operating means connected with the last mentioned piston so as to be operated thereby,

said door operating means passing through the cylinder in which the last mentioned piston is mounted.

2. A door engine of the character described comprising a single acting door opening cylinder opposed by a single acting door closing cylinder of smaller diameter, with an intermediate lubricant chamber, said cylinders being relatively offset, pistons in the respective chambers, a piston rod directly connecting the pistons through said intermediate chamber, said rod being concentric with respect to the smaller piston and eccentric with respect to the larger piston, and a door operating rod also connected with the larger piston so as to be operated thereby, said door operating rod passing through the cylinder in which the larger piston is mounted.

20 3. A door engine comprising a casing provided with two opposed relatively offset cylinders of unequal diameters, pistons reciprocably mounted within and complementary to the respective cylinders, a piston rod rigidly connecting said pistons, and a door operating rod extending from the casing at a position between the pistons and connected with one of the pistons in spaced relation with respect to said piston rod, said casing having means 25 for guiding said door operating rod.

Signed at Albany, county of Albany, and State of New York, this 12th day of August, 1922.

L. P. HYNES.
